Joseph Ames of Bristol Connecticut
Settled Patent

The Schedule referred to in the Settled Patent and forming part of the same containing a description in the words of the said Joseph Ames himself of his improvement in the striking part of Clocks.

To all whom these presents shall come, Joseph Ames of Bristol in the County of Hartford and State of Connecticut, Gentleman, sends greeting. Be it known that I the said Joseph Ames, have invented and contrived, made and applied to use a new and useful improvement in the striking part of common House Clocks, specified in the words following to wit. This improvement consists in what I term a double count wheel, in the striking part of the clock and in the application of the double count wheel to clocks constructed and made with rolling pinions. The count wheel heretofore, and now used in the construction of the striking part of clocks, which I here call the single count wheel, revolves twice in operating regularly, the twenty four hours of the day. That is in regulating one hundred and fifty six strokes of the clock, but the double count wheel I have invented revolves but once in performing the same operation. My double count wheel in making will be seen by the accompanying model by its arranging the various stops for the striking of the hours that the different stops for twelve hours occupy but one half the circle or circumference of the wheel, whereas in the single count wheel over in use the same stops occupy the whole circle or circumference. in the use of the double count wheel the striking of the clock is regulated and the different stops are made in the same manner as in the use of the single count wheel, but in half a revolution of my double count wheel it has all the stops and regulate the same strokes as the single count wheel does in a whole revolution. To make my double count wheel I take or make a wheel of suitable diameter

ings and proportioned for the clock it is to be made in one division and make
out, and make the stops for twelve hours, or half a day, the division on
a single count wheel except that they extend over but one half thereof,
else on a circumference of the wheel, and from the place where the wheel
regulates the striking of twelve strokes for the hours of twelve, begin again
mark out and make the stops in the other half of the circle or circumference
of the wheel, as on the first half of the same so that the strokes
of the clock for twenty four hours of the day are the same as where the
single count wheel is used, but the double count wheel revolves but once
whereas the single count wheel revolves twice in performing that operation.
I consider the best position in the clock for the double count wheel
to be by the side of the first or barrel wheel, in the striking part of the
clock, and attached to the same by division pins extending from one
wheel to the other, and of such length as to fix the count wheel at suf-
ficient distance from the other wheel to give room for the dogs wire
to perform its operations.

What I claim as my invention and is the double count wheel
as distinguished from the single count wheel, and the application of
the double count wheel to clocks constructed with rolling pinsions.
The benefits of this improvement are that the clocks can be made
with less expense, will run with much less weight, and are not as
 liable to get out of repair.

In testimony whereof that the above is a true specification
of my said improvement as above described I have hereunto set
my hand and seal the 12th day of March in the year of our Lord
1833.
